WILLIAM SCHAAKE, OF PITTSBURGH, PENNSYLVANIA, ASSIGNOR TO WESTINGHOUSE ELECTRIC AND MANUFACTURING COMPANY, A CORPORATION OF PENNSYLVANIA.

SUPPORTING STRUCTURE FOR TROLLEY-CONDUCTORS.

1,150,067.

Specification of Letters Patent. Patented Aug. 17, 1915.

Application filed November 8, 1911. Serial No. 659,177.

To all whom it may concern:

Be it known that I, WILLIAM SCHAAKE, a citizen of the United States, and a resident of Pittsburgh, in the county of Allegheny and State of Pennsylvania, have invented a new and useful Improvement in Supporting Structures for Trolley-Conductors, of which the following is a specification.

My invention relates to supporting structures for trolley conductors and it has special reference to structures of this type that are particularly adapted for use in connection with high-speed trolley lines and rail-way electrifications.

The object of my invention is to provide a structure of the above-indicated class that shall be simple, durable and effective in construction and particularly adapted to flexibly support a trolley conductor and to prevent lateral displacement thereof by reason of the lateral thrust produced at curves, as well as by wind and other external forces.

In the past it has been found expedient to employ so-called catenary line construction in connection with high-speed electrifications for the reason that the trolley conductor is yieldingly supported substantially parallel to the track, whereby the trolley wheel or collector is more readily maintained in contact with the trolley conductor and excessive wear of the conductor, due to poor contact and heavy hammer blows at the points of suspension, is eliminated.

In order to maintain the trolley conductor in alinement over the middle of the track and to prevent any sidewise movement thereof, particularly at curves, it has been the practice to employ steadyng means at frequent intervals which usually comprise a steadyng arm, one end of which is pivoted to the pole or supporting bracket, the other end being suitably clamped to the trolley conductor. Although devices of this type prevent lateral displacement, they are not entirely satisfactory for the reason that "hard spots" are produced in the trolley conductor at the points where the devices are clamped thereto, because of the weight of the steadyng arm and a certain component of the lateral strain upon the conductor on curves. As a result of these "hard spots," frequent breakages of the trolley conductor occur, and the repair and mainte-

nance thereof becomes a matter of prohibitive cost.

It is the purpose of my invention to eliminate the difficulties just referred to and to provide a supporting structure which shall be rugged and cheap in construction and shall effectively accomplish the desired results.

My invention is illustrated in the accompanying drawing, in which—

Figure 1 is a view in side elevation of a portion of a supporting structure embodying my invention, and Fig. 2 is an end elevation of the structure shown in Fig. 1.

Referring to the drawing in detail, a pole or post 1 is provided with a laterally projecting bracket or support 2, which is firmly secured in position by a tie rod 3, in accordance with the usual practice. Near the outer end 4 of the supporting bracket 2 is mounted an insulator 5 that is securely attached to the bracket 2 by means of a suitable clamping device 6. The insulator 5 and the clamping device 6 form no part of my present invention and are merely illustrative of any suitable devices for accomplishing the desired results; therefore, no description of the same will be given.

A messenger wire or cable 7 is supported over the top of the insulator 5, although any other suitable method of support may be employed, and a trolley conductor 8 is suspended therefrom at frequent intervals, in a well known manner, by hangers 9.

One end of a steadyng arm 10 of insulating material is pivotally connected to the supporting bracket 2 at a point 11, and the other end 12 thereof is flexibly supported from the messenger wire or cable 7 by straps 13 which diverge upwardly and are respectively secured to the messenger wire or cable 7 on opposite sides of the supporting bracket 2 by U-bolts 14, or other suitable devices. By this means, the weight of the steadyng arm 10 is flexibly carried by the messenger wire 7 through the agency of the straps 13, it being understood that my invention is not restricted to the straps shown but that any other suitable supporting members may be employed.

A short and relatively light arm 15 is movably connected to the inner or free end 105 of the steadyng arm 10 by a horizontal

pivot and projects laterally toward the trolley conductor 8 to which it is rigidly secured by a clamp 16 which may be of any well known construction.

5 Through the agency of the structure just described, the trolley conductor 8 is yieldingly supported in such manner that it is relieved of the weight of the steadyng arm 10 and is merely subjected to the comparatively negligible weight of the arm 15, so that adequate provision is made against lateral displacement of the trolley conductor and, at the same time, the tendency to form "hard spots" therein at the points of attachment, is avoided.

20 Although I have shown and described a supporting structure for trolley conductors having specific structural details and arrangement and location of parts, those skilled in the art will readily understand that many modifications may be effected therein without departing from the spirit and scope of my invention, and I desire that only such limitations shall be imposed as are indicated in the appended claims.

25 I claim as my invention:

1. In an overhead line structure for electric railways, the combination with a messenger wire or cable and a supporting means therefor, of a trolley conductor and clamp therefor, a steadyng arm, a short arm projecting laterally and rigidly from the trolley conductor and pivoted to the end of the steadyng arm, and a pair of supporting members diverging from the end of the steadyng arm and clamped to the messenger wire or cable.

2. In an overhead railway structure, the combination with a messenger cable and a support therefor, of a trolley conductor, a steadyng arm projecting from said support to a point adjacent to the trolley conductor and connected thereto, and a pair of supporting members fastened to the end of the steadyng arm and diverging upwardly to the messenger cable.

3. In an overhead structure for electric railways, the combination with a messenger cable and a support therefor, of a trolley conductor and clamp, a short arm projecting laterally and rigidly from said clamp, a steadyng arm having its end pivoted to one end of said laterally projecting arm, and a pair of diverging supporting members fastened to the steadyng arm and to the messenger cable.

4. In an overhead line structure for electric railways, the combination with a support, a messenger wire or cable supported thereby and a trolley conductor, of a jointed member comprising a long arm secured to said support and a short arm clamped to

said trolley conductor and supporting members diverging from the joint end of said long arm to said messenger cable.

65

5. In an overhead structure for electric railways, the combination with a support and a messenger wire supported thereby, of a steadyng member comprising a long arm having one end pivotally secured to said support and a relatively short laterally disposed arm pivotally connected to its other end, a trolley conductor rigidly clamped to the free end of said short arm, and supporting members for said arms that diverge therefrom to said messenger wire.

70

6. In an overhead line structure for electric railways, the combination with a support, a messenger wire supported thereby, and a trolley conductor, of a steadyng arm having one end pivotally attached to said support and its other end connected to said trolley conductor, and supporting members fastened to said steadyng arm adjacent to the trolley conductor and diverging to the messenger wire on the respective sides of said support.

80

7. An overhead line structure for electric railways comprising a pole, a supporting bracket, an insulator, a messenger wire, a trolley conductor suspended from said messenger wire, a pivotally mounted steadyng arm, means for supporting said arm from said messenger wire, and a short arm pivotally secured to the end of said steadyng arm and rigidly clamped to said trolley conductor.

90

8. An overhead structure for electric railways comprising a messenger wire, a trolley conductor suspended therefrom, a main steadyng arm, means for suspending one end of said arm from said messenger wire, and a short auxiliary steadyng arm pivotally secured to the suspended end of said main arm and rigidly attached to said trolley conductor.

95

9. An overhead structure for electric railways comprising a support, a messenger wire carried thereon, a trolley conductor suspended from said messenger wire, a steadyng arm to prevent substantially all lateral displacement of said trolley conductor and means for applying the strain exerted by the weight of said steadyng arm in an approximately vertical plane to a plurality of points on the messenger wire.

100

10. In testimony whereof, I have hereunto subscribed my name this 31st day of Oct., 1911.

WILLIAM SCHAAKE.
